BAND-PASS FILTER

Harold A. Wheeler, Great Neck, N. Y., assignor to
Hazeltine Corporation, a corporation of Dela-
ware

Application June 10, 1935, Serial No. 25,737

16 Claims. (Cl. 178—44)

My invention relates to band-pass filters and more particularly to composite filters including a plurality of separate band-pass filters co-operating to pass a more extended band than any of the filters individually.

While my invention is of general application, it is especially suitable for coupling portions of an antenna system of a radio-frequency signaling system adapted to receive or transmit a wide band, or a plurality of bands, of the radio-frequency spectrum.

In many installations, particularly in radio-frequency receiving and transmitting circuits, it is desired to pass a wide band of frequencies, or selectively to pass any of a plurality of frequency bands aggregating a wide portion of the radio-frequency spectrum. For example, such a wide frequency band may be bounded by frequencies having a ratio on the order of 40 to 1. However, certain difficulties are presented in the design of a band-pass filter operating between extreme frequency limits, both as to the complexity or number of filter elements required and the actual circuit design, and as to the procurement of reasonably uniform responsiveness over the band. More particularly in the case of a wide band filter which must include a transformer to separate the input and output circuits or to match their respective impedances, it becomes difficult, if not impossible, to design a single transformer capable of passing such a wide band of frequencies, for such a transformer would require a coefficient of coupling very near unity. In other words, a given coefficient of coupling in a transformer places a limit on the ratio of the boundary frequencies of the band which can be passed by a filter utilizing the transformer.

It is an object of my invention, therefore, to provide a composite band-pass filter capable of passing a wide band of frequencies, which will overcome the above-mentioned difficulties of the arrangements of the prior art, and which will require a minimum of circuit elements.

More specifically, it is an object of my invention to provide a composite band-pass filter capable of covering a wide band of frequencies and including a plurality of band-pass filters each having a transformer section and designed individually to pass a plurality of frequency bands separated by intervening frequency bands, the co-operating filters being proportioned and poled so as to pass a resultant continuous band

comprising the pass bands and the intervening bands.

In accordance with my invention, there are provided two or more constant-k derived band-pass filters each comprising at least two band-pass half-sections of any of several suitable types and including a transformer section, said filters being of similar type and termination and being similarly connected to common terminal circuits. Both terminal sections of each individual filter are of such type and are so proportioned that corresponding terminal sections of all the filters may be directly interconnected both at the input end and at the output end of the resultant network. The several filters are designed individually to pass a plurality of bands separated by intervening bands and to co-operate in passing the frequencies of the intervening bands, resulting in an image impedance characteristic similar to that of a single constant-k continuous-band filter passing the extended frequency range.

In the drawings, Fig. 1 is a schematic diagram of a complete antenna system including a composite band-pass filter employing my invention; Figs. 2 and 3 are approximately equivalent simplified circuit diagrams of the system of Fig. 1 when operating in the short wave and long wave bands, respectively; Figs. 4a—4b are circuit diagrams illustrating the circuit transformations in developing the high-frequency filter component; Figs. 5a—5b are corresponding diagrams for the low-frequency component of the filter of Fig. 1; Fig. 6 is a composite equivalent circuit diagram of the networks of Figs. 4 and 5; Fig. 7a is a graph representing the individual image impedance characteristics of the filters of Figs. 4b and 5b; while Fig. 7b is a graph of the image impedance characteristic of the composite filter of Fig. 6.

Referring now more particularly to Fig. 1, there is shown schematically a wave-signal-collecting system to which my invention is particularly suitable and in which it is embodied as a composite filter for coupling a transmission line from the antenna to a signal-translating or load device, such as a radio receiver. The general system of Fig. 1 is disclosed and claimed in my copending application Serial No. 25,735, filed June 10, 1935, and patented December 15, 1936 as U. S. Patent No. 2,064,774 so that a detailed description thereof is considered unnecessary.

In general, the system includes an antenna 10a—10b, preferably designed as a doublet for 55

operation in the high-frequency portion of the band to be covered, and for operation as a simple, flat-top antenna over the low-frequency portion of the band. The antenna 10a-10b is 5 coupled to a transmission line 12 by a band-pass filter 11 of a suitable type. One type of composite extended range band-pass filter, particularly suitable for this purpose, is disclosed and claimed in my copending application Serial No. 10 25,736, filed June 10, 1935 and patented December 15, 1936 as U. S. Patent No. 2,064,775.

The other end of the transmission line 12 is coupled to a signal-translating or load device 14, such as a radio receiver, having an input circuit 15 the impedance of which is indicated at 15, by means of a composite filter 13 designed in accordance with my present invention. The composite filter 13 is designed and proportioned to pass an extended band of frequencies, for example, from 0.5 to 20 megacycles. It is desired that the composite filter 13 shall approximately match the constant image impedance of the line 12 with the impedance 15 of the input circuit of the load device 14. It is also desirable that 20 the composite filter shall include transformer sections which avoid direct connections between the primary and secondary circuits of the filter and permit impedance transformation, since, in general, the image impedance of the line will 25 have a value different from that of the load device 14.

The composite filter 13 comprises a plurality of filters of similar type and termination, similarly connected between common terminal circuits and designed individually to pass certain frequency bands spaced by intervening frequency bands. While my invention is applicable to a composite filter in which the boundary frequencies defining the individual pass bands and intervening bands are related in any predetermined manner, it is particularly useful in such a composite filter in which the boundary frequencies are related approximately in an arithmetic or geometric progression; that is, the width of each 35 of the intervening bands is the arithmetic or geometric mean of the adjacent bands. When the arithmetic relationship between the boundary frequencies obtains, the resultant filter is characterized by very nearly equal velocities of propagation for all frequencies within the aggregate band, which is the condition for minimum distortion of a complex wave. For the purposes of explanation and calculation it will be assumed that the complete frequency band, for example, 40 0.5-20 megacycles, is divided into three bands by the boundary frequencies f_1 , f_2 , f_3 , and f_4 having values, respectively, of 0.5, 1.7, 5.8 and 20 megacycles, these frequencies being related approximately in a geometric progression in which the 45 mean constant of progression, which is also the ratio of the upper to the lower boundary frequency of each band, is 3.4. In fact, in order fully to utilize the advantages of my invention, it is desirable that each component band shall 50 be relatively wide, that is, that the ratio of its upper to its lower boundary frequencies shall be substantially greater than unity—in the example given, having an average value of 3.4, as stated above.

70 It has become common practice in the design of band-pass filters to base the design on a filter section of a standard type. For the purpose of preliminary computations, an arbitrary value may be assumed for the nominal input and output image impedances. A type is generally cho-

sen the input and output impedance characteristics of which are similar and have the same nominal value, which is the value at the frequency for which the slope of the image impedance curve is zero. This nominal value is indicated by the 5 symbol R which may be assumed to be 100 ohms, for the purposes of preliminary computation. A particular filter section found to meet the requirements of this invention is shown in Fig. 4a and referred to hereinafter as type A. (For a 10 more complete description of the several types of symmetrical band-pass filter sections suitable for use in the preferred embodiment of this invention and discussed herein, reference is made to a textbook of T. E. Shea—Transmission Networks and Wave Filters, D. Van Nostrand Co., 1929). The type A filter section is referred to at page 316 of the Shea reference as of the type III, which, it will be noted, is a constant-k derived type having a mid-shunt image impedance 15 similar to that of the basic constant-k type. 20

The type A filter section of Fig. 4a comprises a mid-shunt condenser 16 and inductance 17, a full-series inductance 18 and a mid-shunt condenser 19 and inductance 9. Such a half-section permits the insertion of a transformer, since it includes both series and parallel inductances which may be realized by the self- and mutual inductances of transformer windings in an equivalent network. It will be assumed that the type 30 A section, Fig. 4a, is to be designed for operation over the frequency band f_3-f_4 . It will also be assumed that the section A is to be designed for equal image impedances R of 100 ohms at both input and output circuits. The values of the 35 circuit reactances may then be computed, in terms of R and the boundary frequencies of the band which the section is to pass, either from the formulas given by Shea on page 316 or by such formulas modified for a single section with 40 mid-shunt termination, such as the type A section, as given in the appended table for Fig. 4a, type A.

By the use of well-known equivalent-circuit 45 transformations, section A of Fig. 4a can be converted into the section illustrated in Fig. 4b, hereinafter referred to as a type B section. In this transformation the inductances 17, 18 and 50 9 are converted into the equivalent inductances 21 and 23 and mutual inductance therebetween, 55 these inductances constituting primary and secondary windings of a transformer. In the computation of the values of the circuit elements of the section B, however, it is necessary to multiply all the reactances of the primary circuit of 60 this section by the ratio of the image impedance R_L of the line 12 to the assumed image impedance R of the filter section of Fig. 4a. Similarly, in order to match the secondary circuit of the section B to the input impedance 15, it is necessary 65 to multiply the several reactances of the secondary circuit by the ratio of the impedance R_A of the input circuit 15 to the assumed image impedance R. The formulas for the circuit constants of the type B filter section, including the 70 circuit transformations and the factors for matching the primary and secondary impedances, are given in the appended table for Fig. 4b, type B.

The image impedance characteristic of the 70 primary circuit of section B is represented by the curve X of Fig. 7a, from which it is seen that the minimum image impedance is equal to the image impedance R_L of the line 12. The characteristics of the filter section B are the same 75

on the secondary side except that the actual values are modified to match the impedance R_A of the input circuit 15. This curve has the shape of the well-known constant-k mid-shunt image impedance curve, and may therefore be so designated.

The component band-pass filter for operation over the low-frequency band f_1-f_2 , for example, 0.5 to 1.7 megacycles, may be similar to that described, as modified for the different boundary frequencies. The theory of design of the low-band filter is the same as that of the high-band filter described above. Referring to Fig. 5a, the starting point is again a filter section of type A having a constant-k image impedance of nominal value R , say 100 ohms. The section A of Fig. 5a comprises a mid-shunt condenser 24 and inductance 25, a full-series inductance 26, and a mid-shunt condenser 27 and inductance 28. The formulas for the design of the circuit of Fig. 5a are the same as those for Fig. 4a with the exception of the change of boundary frequencies. These formulas are given in the appended table for Fig. 5a, type A.

25 The low-band filter section of Fig. 5a may be transformed to that of Fig. 5b in a manner similar to that in which the high-band filter section was transformed. There results a type B filter section comprising a primary condenser 29 and inductance 30 and a secondary condenser 31 and inductance 32. In this case, also, in effecting the circuit transformation the primary and secondary reactances are multiplied by the ratios R_L/R and R_A/R , respectively. The formulas for the circuit constants of the type B section of Fig. 5b, including the circuit transformations and the factors for matching the primary and secondary impedances, are given in the appended table for Fig. 5b, type B.

40 The image impedance characteristic of the primary circuit of the filter section of Fig. 5b is represented by the curve Y of Fig. 7a, from which it is seen that the minimum image impedance is equal to the image impedance R_L of the line 12. 45 As in the case of the high-band filter, the characteristics of the filter section are the same on the secondary side, but the actual values are modified to match the impedance R_A of the input circuit 15. Curve Y, like curve X, is a constant-k mid-shunt image impedance curve.

50 The high-band and low-band filter sections of Figs. 4b and 5b may be combined into the composite filter section of Fig. 6, hereinafter referred to as type C, in which both the primary and secondary circuits are similarly connected individually between common terminal circuits. By the term "similarly connected" is meant that both filters are connected to each terminal circuit with the same polarity and that the circuits of both 55 filters on both the primary and secondary sides are similarly related to each other, in this case being connected in series. In addition, the inductance 21 of the primary circuit is split into two 60 sections 21a and 21b in order to maintain the balance of the line 12. Two band filters of the 65 type shown in Figs. 4b and 5b having characteristics X and Y, respectively, if combined in this manner and if designed to pass bands bounded by the frequencies f_1-f_2 and f_3-f_4 , respectively, in 70 which the frequencies f_1, f_2, f_3, f_4 are approximately in the relation of a geometric progression, will operate substantially independently over their respective bands, but will co-operate to pass the intervening band. It will be seen that curves X 75 and Y indicate that the image impedances of their

respective filter sections both have substantially infinite values at the cut-off frequencies f_2 and f_3 bounding the intervening band. This relationship enables the high-band and low-band filters to be combined to secure the resultant image impedance characteristic Z, Fig. 7b, which is a constant-k mid-shunt image impedance curve for the band f_1-f_4 . It will be seen from this curve that the resultant image impedance is approximately uniform not only over the pass bands f_1-f_2 and f_3-f_4 , but also over the intervening band f_2-f_3 . While the formulas given above for computing the reactance values of the circuits of Figs. 4b and 5b may be used with approximate accuracy for the type C composite filter of Fig. 6, there is a certain amount of interaction between the circuits, and more exact formulas are given in the appended table for computation of the reactance values of the type C composite filter, Fig. 6. In these formulas, attention is called to the fact that the inductance L_{21} is the total inductance of the combined coils 21a and 21b.

25 While the formulas given above for the computation of the individual band-pass filters may be used in the design of the composite filter with approximately the characteristics described, the two band filters have a certain amount of mutual interaction and for exact results it is preferable to compute the entire system as a single filter. Such computations may be based upon the fundamental short-circuit—open-circuit methods of filter design described at pages 75-84 and 179-208 of the above Shea reference. The resultant modified formulas for the type C composite filter 30 of Fig. 6 are given in the appended table under such heading. It will be noted that the formula for the parameter h of these formulas is the reciprocal of the constant of the geometric progression of the boundary frequencies of the component bands; it follows that h should have a value much 35 less than unity—in the example given being 0.29.

40 By the use of my invention, as described, it is possible to design a band-pass filter to pass any required wide range of frequencies, and including several transformers of reasonable coupling. 45 While individual filter sections of the type described are particularly suitable because of their relatively low attenuation outside their respective bands, other filter sections having generally similar characteristics may be substituted therefor, 50 provided that they have at each common terminal circuit similar extreme values of image impedance at the cut-off frequencies bounding each intervening band.

55 While I have shown a composite filter comprising only two band-filter sections, it is clear that the principles involved may be extended to any number of filter sections. For example, the inductance 30 may be split for the insertion of the primary circuit of a third band-filter, while 60 the lower connection between the inductance 32 and condenser 31 may be broken to insert the secondary circuit of a third band-filter, and this procedure may be repeated to include as many sections as desirable for any particular installation.

65 It is to be noted that the shunt condensers 20 and 22 are in parallel not only with their respective inductances 21 and 23 but also with the inductances 30 and 32, respectively, which 70 are of larger inductance for operation over a lower frequency band. On the other hand, the shunt condensers 29 and 31 are in series with the high-frequency filter inductances 21 and 23, respectively. In case of the extension suggested 75

- in the preceding paragraph, the same relationship would obtain. In other words, in a composite filter of the type described, if all the condensers and inductances on each side are numbered serially in their order of increasing inductance and capacitance, respectively, and the elements of the same serial number are connected to form individual band-pass filters, the inductances of each of the primary and secondary circuits being all in series, each condenser will be connected in shunt with its respective inductance of like serial number and, in addition, with only those inductances of higher serial number. By this arrangement, the condensers of the high-band filter sections serve to by-pass from the low-band filter inductances, frequencies which might correspond to natural frequencies of the coils of greater inductance, and therefore might otherwise be affected abnormally.
- 20 The composite filter of Fig. 6 is identical to the filter 13 of Fig. 1, save only that the condenser 29 of Fig. 1 has been split into two equal series components to provide a neutral or mid-tap ground connection for the balanced line 12, to maintain the balance of the line and at the same time provide a ground connection in which may be inserted a proper terminating impedance 33 for unbalanced currents in the line. The transformer comprising the windings 30 and 32 of the low-band filter may be provided with a core of finely divided iron, such, for example, as that marketed under the name "Ferrocarr".
- It is believed that the general principles of operation of the above-described system will be clear from the foregoing detailed description of the circuit arrangements and the principles involved in its design. However, the operation in the several frequency bands may be summarized by reference to Figs. 2 and 3, each of which includes only the circuit elements primarily active in its respective frequency band. It will be clear that the inductances of the low-band filter have such high impedances over the high-frequency band that their admittances may be neglected, while the condensers of this filter have such low impedances that they may be considered as short circuits, so that the low-band filters have very little effect on the high-band operation. Similarly, the inductances and capacitances of the high-band filter have little effect on the operation over the low-frequency band. In the intervening frequency band, f_2-f_3 , the reactance elements of the two component band filters are all effective in determining the operation.
- 55 Referring specifically to Fig. 2, it will be seen that the high-band filter component is effective in the high band f_3-f_4 to transfer signals received from the line 12 to the input circuit 15, at the same time substantially matching the impedance of the line 12 with that of the input impedance 15. In Fig. 3 the low-band filter similarly operates over the low band f_1-f_2 to couple the line 12 and the input circuit 15. In Fig. 1 the two individual band-filters cooperate over the intervening frequency band f_2-f_3 to couple the transmission line 12 to the input impedance 15, at the same time matching the impedances of these two devices. With the arrangement described above, each of the transformers 21a, 21b, 23 and 30, 32 may have a coefficient of coupling that may be readily realized in practice, while the composite filter is effective to pass a frequency band for which a single transformer could be designed only with difficulty, if at all.

While the composite band filter above-described may be designed for operation over a wide range of conditions, by way of example only there are given herewith the circuit constants of a particular composite filter for operation over the frequency ranges defined by the above-mentioned boundary frequencies and embodying my invention in the form described above. The following circuit values were realized as closely as possible and include such effects as inherent capacitance or inductance of other related circuit elements:

$$\begin{aligned} f_1 &= 0.5 \text{ megacycle} \\ f_2 &= 1.7 \text{ megacycles} \\ f_3 &= 5.8 \text{ megacycles} \\ f_4 &= 20 \text{ megacycles} \end{aligned} \quad 15$$

Line image impedance $R_L = 500$ ohms resistance

Load impedance $R_A = 400$ ohms resistance

Elements: 21a + 21b = 27 microhenries

$$\begin{aligned} 23 &= 21 \text{ microhenries} \\ 30 &= 262 \text{ microhenries} \\ 32 &= 210 \text{ microhenries} \\ 20 &= 16 \text{ micro-microfarads} \\ *22 &= 20 \text{ micro-microfarads} \end{aligned} \quad 20$$

*Capacitance 22 was physically a part of the inherent capacitance between coil 23 and the adjacent shield.

Transformer 21a, 21b, 23

Coefficient of coupling—84%.

Transformer 30, 32

Coefficient of coupling—84%.

While I have described what I at present consider the preferred embodiment of my invention, it will be obvious to those skilled in the art that various changes and modifications may be made therein without departing from my invention, and I, therefore, aim in the appended claims to cover all such changes and modifications as fall within the true spirit and scope of my invention.

30 What I claim is:

1. A continuous-band filter comprising the combination of a plurality of constant-k derived band-pass filters of similar type and termination connected individually between common terminal circuits, the several filters being similarly connected to both terminal circuits, said band-pass filters being adapted individually to pass frequency bands spaced by intervening bands each having a width equal to a mean value of the widths of the adjacent pass bands, and said band-pass filters being relatively poled and proportioned to pass a resultant continuous band comprising said pass bands and intervening bands.

2. A continuous-band filter comprising the combination of a plurality of constant-k derived band-pass filters of similar type and termination connected individually between common terminal circuits, the several filters being similarly connected to both terminal circuits, said band-pass filters being adapted individually to pass frequency bands spaced by intervening bands, the boundary frequencies of said bands being related approximately in a geometric progression, and said band-pass filters being relatively poled and proportioned to pass a resultant continuous band comprising said pass bands and intervening bands.

3. A continuous-band filter comprising the combination of a plurality of constant-k derived band-pass filters of similar type and termination connected between common terminal circuits, each of said band-pass filters comprising at least two inductively coupled inductances effectively connected, respectively, to said terminal circuits and each having capacitance means effectively in parallel therewith, corresponding inductances of all said filters being connected in series across their respective terminal circuits, said band-pass filters being adapted individually to pass frequency bands spaced by intervening bands each having a width equal to a mean value of the widths of the adjacent pass bands, said band-pass filters being relatively poled and proportioned to pass a resultant continuous band comprising said pass bands and intervening bands.

75 4. A continuous-band filter comprising the

combination of a plurality of constant-k derived band-pass filters of similar type and termination connected between common terminal circuits, the several filters being similarly connected to both terminal circuits, each of said band-pass filters comprising at least two inductively coupled inductances effectively connected, respectively, to said terminal circuits and each having capacitance means effectively in parallel therewith, corresponding inductances of all said filters being connected in series across their respective terminal circuits, said band-pass filters being adapted individually to pass frequency bands spaced by intervening bands, the boundary frequencies of said bands being related approximately in a geo-

metric progression, said band-pass filters being relatively poled and proportioned to pass a resultant continuous band comprising said pass bands and intervening bands.

5. A continuous-band filter comprising a primary circuit and a secondary circuit, a plurality of inductively coupled sets of primary and secondary inductances of which each set may be identified by a serial number in the order of increasing inductance, and a plurality of sets of primary and secondary condensers of which each set may be identified by a serial number in the order of increasing capacitance, said primary inductances being connected in series across the primary circuit and each of said primary condensers being connected in parallel with certain of said primary inductances including that identified by the same serial number and in series with those identified by lesser serial numbers, said secondary inductances and capacitances being similarly connected across said secondary circuit, all the elements identified by each serial number being proportioned to form an individual band-pass filter, the respective pass bands of all such individual filters being spaced by intervening bands each having a width equal to a mean value of the widths of the adjacent pass bands, and said band-pass filters being relatively poled and proportioned to pass a resultant continuous band comprising said pass bands and intervening bands.

6. A continuous-band filter comprising a primary circuit and a secondary circuit, a plurality of inductively coupled sets of primary and secondary inductances of which each set may be identified by a serial number in the order of increasing inductance, and a plurality of sets of primary and secondary condensers of which each set may be identified by a serial number in the order of increasing capacitance, said primary inductances being connected in series across the primary circuit and each of said primary condensers being connected in parallel with certain of said primary inductances including that identified by the same serial number and in series with those identified by lesser serial numbers, said secondary inductances and capacitances being similarly connected

- across said secondary circuit, all the elements identified by each serial number being proportioned to form an individual band-pass filter, the respective pass bands of all such individual filters being spaced by intervening bands, the boundary frequencies of said bands being related approximately in a geometric progression, and said band-pass filters being relatively poled and proportioned to pass a resultant continuous band comprising said pass bands and intervening bands.
7. A continuous-band filter comprising a primary circuit and a secondary circuit, a plurality of inductively coupled sets of primary and secondary inductances of which each set may be identified by a serial number in the order of increasing inductance, and a plurality of sets of primary and secondary capacitances of which each set may be identified by a serial number in the order of increasing capacitance, said primary inductances being connected in series across the primary circuit and each of said primary capacitances being connected in parallel only with all those of said inductances identified by equal and greater serial numbers, said secondary inductances and capacitances being similarly connected across said secondary circuit, all the elements identified by each serial number being proportioned to form an individual band-pass filter, said individual filters being of the same type and the respective bands of all such individual filters being spaced by intervening bands, the boundary frequencies of said bands being related approximately in a geometric progression, and said band-pass filters being relatively poled and proportioned to pass a resultant continuous band comprising said pass bands and intervening bands.
8. A continuous-band filter comprising the combination of a plurality of band-pass filters of similar type and termination connected between common terminal circuits, said band-pass filters being adapted individually to pass frequency bands spaced by intervening bands, the boundary frequencies of said bands being related approximately in a geometric progression, each of said band-pass filters being of type B and proportioned approximately according to the formulas for type B, and said filters being relatively poled to pass a resultant continuous band comprising said pass bands and intervening bands.
9. A continuous-band filter comprising the combination of a pair of band-pass filters of similar type and termination connected between common terminal circuits, said band-pass filters being proportioned individually to pass a pair of frequency bands spaced by an intervening band, the boundary frequencies of said bands being related approximately in a geometric progression and said filters co-operating to form a composite filter of type C and proportioned approximately according to the formulas for type C to pass a resultant continuous band comprising said pass bands and intervening bands.
10. A continuous-band filter comprising the combination of $n/2$ band-pass filters of similar type and termination connected between common terminal circuits, each of said band-pass filters comprising a transformer having primary and secondary windings effectively connected, respectively, to said terminal circuits and each having capacitance means effectively in parallel therewith, corresponding windings of all of said filters being connected in series across their re-

spective terminal circuits, said band-pass filters being adapted individually to pass alternate frequency bands spaced by intervening bands, said bands being bounded by frequencies $f_1, f_2 \dots f_n$ related approximately in a geometric progression, the coefficient of coupling of each of said transformers being determined by the formula

$$k = \frac{1-h^2}{1+h^2}$$

where

$$h = \left(\frac{f_1}{f_n} \right)^{\frac{1}{n-1}}$$

the value of h being much less than unity and said band-pass filters being relatively poled and proportioned to pass a resultant continuous band comprising said pass bands and intervening bands.

11. A continuous-band filter comprising the combination of a pair of band-pass filters of similar type and termination connected between common terminal circuits, each of said band-pass filters comprising a transformer having primary and secondary windings, a winding of the transformer of the higher-band filter being divided into sections with the corresponding winding of the lower-band filter being interposed therebetween and having a lower-band filter condenser connected in shunt thereto, said serially connected windings being connected across a common terminal circuit and having a higher-band filter condenser connected in shunt thereto, the other windings of said transformers being serially connected across the other terminal circuit and having a higher-band filter condenser connected in shunt thereto and a lower-band filter condenser connected in shunt to its respective winding, said band-pass filters being adapted individually to pass frequency bands spaced by intervening bands, the boundary frequencies of said bands being related approximately in a geometric progression, said band-pass filters being relatively poled and proportioned to pass a resultant continuous band comprising said pass bands and intervening bands.

12. A continuous-band filter comprising the combination of a plurality of constant- k derived band-pass filters connected individually between common terminal circuits, the several filters being similarly connected to both terminal circuits, said band-pass filters being adapted individually to pass frequency bands each bounded by cut-off frequencies having a ratio much greater than unity, said frequency bands being spaced by intervening bands each having a width equal to a mean value of the widths of the adjacent pass bands, and said band-pass filters being relatively poled and proportioned to pass a resultant continuous band comprising said pass bands and intervening bands.

13. A continuous-band filter comprising the combination of a plurality of band-pass filters connected individually between common terminal circuits, said band-pass filters being adapted individually to pass frequency bands each bounded by cut-off frequencies having a ratio much greater than unity, said frequency bands being spaced by intervening bands each having a width equal to a mean value of the widths of the adjacent pass bands, said band-pass filters having individually at either terminal circuit similar extreme values of image impedance at the cut-off frequencies bounding each intervening band, and said band-pass filters being relatively poled and proportioned substantially to secure over said intervening

ing bands a uniform resultant image impedance at each common terminal circuit.

14. A continuous-band filter comprising the combination of a plurality of constant-k derived 5 band-pass filters connected individually between common terminal circuits, the several filters being similarly connected to both terminal circuits, said band-pass filters being adapted individually to pass frequency bands each bounded by cut-off 10 frequencies having a ratio much greater than unity, said frequency bands being spaced by intervening bands each having a width not exceeding the arithmetic mean value of the widths of the adjacent pass bands, and said band-pass 15 filters being relatively poled and proportioned to pass a resultant continuous band comprising said pass bands and intervening bands.

15. A continuous-band filter comprising the combination of a plurality of band-pass filters 20 connected individually between common terminal circuits, each of said band-pass filters comprising at least two inductively coupled inductances effectively connected, respectively, to said terminal circuits and each having capacitance means 25 connected therewith, said band-pass filters being adapted individually to pass frequency bands each bounded by cut-off frequencies in a ratio much greater than unity, said frequency bands being spaced by intervening bands each having a width equal to a mean value of the

widths of the adjacent pass bands, and said band-pass filters being relatively poled and proportioned to pass a resultant continuous band comprising said pass bands and intervening bands.

16. A continuous-band filter comprising the 5 combination of a plurality of constant-k derived band-pass filters of similar type and termination connected between common terminal circuits, the several filters being similarly connected to both terminal circuits, and each of said band-pass filters comprising only primary and secondary inductances coupled only inductively and effectively connected, respectively, to said terminal circuits and each having capacitance means effectively in parallel therewith, corresponding inductances of all said filters being connected in series 10 across their respective terminal circuits, said band-pass filters being adapted individually to pass frequency bands each bounded by cut-off 15 frequencies having a ratio much greater than unity, said frequency bands being spaced by intervening bands each bounded by frequencies having a ratio on the order of the geometric mean value 20 of the cut-off frequency ratios of the adjacent pass bands, and said band-pass filters being relatively poled and proportioned to pass a resultant 25 continuous band comprising said pass bands and intervening bands.

HAROLD A. WHEELER.
